UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

MUSHROOM-BULLET.

1,081,616.

Specification of Letters Patent. Patented Dec. 16, 1913.

Application filed September 13, 1913. Serial No. 789,602.

To all whom it may concern:

Be it known that I, THOMAS C. JOHNSON, a citizen of the United States, residing at New Haven, in the county of New Haven 5 and State of Connecticut, have invented a new and useful Improvement in Mushroom-Bullets; and I do hereby declare the following, when taken in connection with the accompanying drawings and the characters of 10 reference marked thereon, to be a full, clear, and exact description of the same, and which said drawings constitute part of this application, and represent, in—

Figure 1, a view in side elevation of a 15 mushroom bullet constructed in accordance with my invention, a portion of the jacket being broken away, exposing a portion of the core in section. Fig. 2, a corresponding view of one of the modified forms which 20 my invention may assume.

My invention relates to an improvement in that class of mushroom bullets in which a jacket of thin sheet-metal is swaged upon a core of soft metal, the object being to produce at a low cost for manufacture, a superior bullet of the character described.

With this end in view my invention consists in a mushroom bullet having certain 30 details of construction as will be herein-after described and pointed out in the claim.

In carrying out my invention as shown in Fig. 1 of the drawings, the one-piece jacket of relatively hard sheet-metal is virtually divided into a tip, 2, and a body, 3, 35 by the formation in it of a continuous circumferential groove, 4, entering the jacket at a right angle to the longitudinal axis of the bullet and stretching and weakening the metal of the jacket which is forced directly inward into the soft-metal core which 40 completely fills the tip and body of the jacket. At the moment of impact, this bul-

let collapses and mushrooms along the weakened circumferential line created by the formation of the circumferential groove, 45 4, which is of substantially triangular cross-section as shown.

In the modified construction shown by Fig. 2, the one-piece sheet-metal jacket is virtually divided into a tip, 2, and a body, 50 3, by means of a circumferential groove 6, substantially rectangular in cross-section and forced slightly inward into the soft-metal core, 5, at a right angle to the longitudinal axis of the bullet. The production of the groove, 6, also weakens the jacket by stretching the metal of the same and so weakens the jacket at this point that the bullet is disrupted along the line of the groove and caused to mushroom at the moment of impact.

I claim:

As a new article of manufacture, a full-jacketed, sharp-nosed mushroom bullet cylindrical at its rear end and tapering at its 65 forward end to a point, the said bullet comprising a soft-metal core and a jacket of uniform thickness therefor, and the bullet being provided in its tapering point and forward of its largest diameter with a circumferential groove formed in the jacket and extending into the core and virtually dividing the one-piece jacket into tip and body-portions, whereby the tip-portion of the jacket is adapted to be telescoped into 70 75 the body-portion thereof and the same disrupted, and the bullet mushroomed.

In testimony whereof, I have signed this specification in the presence of two subscribing witnesses.

THOMAS C. JOHNSON.
